UNITED STATES PATENT OFFICE.

OTTO E. HUEBNER, OF TOLEDO, OHIO, ASSIGNOR TO INDUSTRIAL RESEARCH CORPORATION, OF TOLEDO, OHIO, A CORPORATION OF DELAWARE.

IGNITION SYSTEM.

Application filed January 11, 1919. Serial No. 270,684.

To all whom it may concern:

Be it known that I, Otto E. HUEBNER, a citizen of the United States, residing at Toledo, Ohio, in the county of Lucas and 5 the State of Ohio, have invented certain new and useful Improvements in Ignition Systems, of which I declare the following to be a full, clear, and exact description.

This invention relates to improvements in 10 ignition systems for internal combustion engines and consists principally in the provision of means for increasing the permeability of the field of the induction coil, whereby the mutual inductance of the primary and sec- 15 ondary windings is increased, thus increasing the electromotive force induced in the secondary and improving the spark produced in the spark plug.

So far as I am aware, induction coils for 20 gas engine ignition systems heretofore have been built with fixed amounts of metal in their magnetic paths. At starting and at low engine speeds, a magnetic path of consider- 25 able permeability is desirable, in order that there may be a large inductance, the time interval between each make and break in the primary circuit being sufficient to permit the current to approach more or less closely the maximum value possible. At 30 high engine speeds, the time interval referred to is much smaller, and consequently it is desirable to reduce the permeability of the magnetic path of the coil in order to reduce the lag in the current and give it an opportunity to build up. Because of these 35 conditions a coil built for maximum efficiency at high engine speeds produces an unsatisfactory spark at starting.

It is the principal object of my invention 40 to provide a coil which is capable of giving something near the maximum efficiency both at starting and at high engine speed.

Another object of the invention is to provide means whereby the permeability of the 45 magnetic path of the coil may be increased during low running speed of the engine.

A further object of the invention is to provide means for producing an increase in the permeability of the magnetic path of 50 the coil by the actuation of the means which set in motion the engine starting motor, thus providing good ignition while the current through the coil is reduced by the consumption of the starting motor.

55 Other objects and objects relating to de-

tails of construction and economies of manufacture will appear as I proceed with the description of that embodiment of the invention which, for the purposes of the present application, I have illustrated in the accompanying drawing, in which:

Figure I is a diagrammatic view of my invention as applied to an engine having an electric starting motor.

Figure II is a similar view showing a portion only of the circuits and apparatus to which a modified form of the invention is applied.

Figure III is a diagrammatic view showing a further modification in which the metallic conductor for the magnetic lines of force is arranged to be moved toward and away from the coil by means entirely separate from any other control.

Figure IV is a diagrammatic view showing an electro-magnetic means actuated while the starting motor is in operation for drawing the magnetic conductor into position to shorten the magnetic path.

Similar reference characters refer to similar parts throughout the views.

In the drawing the gas engine is not illustrated, but its spark plugs are diagrammatically indicated at 10. In this case they are shown as four in number although the invention is applicable to an engine with any number of cylinders and spark plugs. A current distributor 11 carries the current to the spark plugs in the different cylinders at the proper times for explosion of the charges, the distributor being driven at cam shaft speed. The current interrupter 12 is also driven at cam shaft speed and is so timed with respect to the distributor as to break the primary circuit each time that a secondary or high tension circuit is established through one of the spark plugs.

A condenser 13 is shunted around the interrupter 12 to reduce sparking, as will be well understood. The primary circuit includes a battery 14 or other suitable current source, the primary winding 15 of an induction coil and a switch 16. The secondary winding 17 of the induction coil is joined to the distributor at one end and at the other to the ground.

As shown in Figure I, the battery 14 may be employed also to supply current to an electric starting motor 18 which, for purposes of illustration only, is shown sup-

plied with a series field 19. In the motor circuit I have shown a push-button switch 20 normally held open by a spring 21. The closing of this switch puts the starting motor in circuit with the battery to start the engine. This is a preferred embodiment, but I desire it to be understood that any means of starting the engine may be employed without departing from my invention in its broad aspect.

In the drawing I have shown three different ways for regulating the amount of metal in the magnetic path of the ignition coil. In each of the views the numeral 22 represents a metallic core, while in Figures II, III, IV I have illustrated in addition metal shells 23, 24 and 29 respectively. The shells serve the same purpose as the cores, that is they all constitute paths of low reluctance for the magnetic lines of force. In Figure I the core 22, in Figure II the shell 23, and in Figures III and IV both the core and shell are movable longitudinally of the induction coil. Any suitable means for accomplishing this movement may be employed, but I prefer to make use of a Bowden wire connection 25, which enables me to locate the control button 20 in any desirable and convenient position as, for instance, upon the instrument board or in the floor of an automobile. Also this type of connection lends itself readily to attachment to a control lever for any type of power driven engine starter. I have illustrated it only as connected to the switch controlling an electric starting motor, but its application to other kinds of motors will be obvious.

In Figure II the core 22 is immovable and extends beyond the coil at one end 26 in order to form a guide for the smaller portion 27 of the shell 23. In Fig. III I have shown the control button as unattached to any starting device, but as conveniently located for operation at any time either at starting or while the engine is running at low speed.

In Figure IV I have illustrated an electro-magnetically operated means for moving the core and shell to reduce the length of the magnetic path of the coil. In the present instance, this means consists of a coil 28 of low resistance wire surrounding the shell 29 and connected by means of circuit wires 30 and 31 in parallel with the starting motor 11. A spring 32 tends to hold the core 22 and shell 29 partially out of the coil. Whenever a current of sufficient strength is passed through the coil 28, the magnetic lines of force induced thereby exert a pull upon the shell 29 which acts against the tension of spring 32 to draw the core and shell into closer union with the coil, thus increasing the permeability of the field as heretofore explained. Any source of cur-

rent may be connected across the wires 30, 31 and a switch for controlling the circuit may be located in any desired position, but I prefer to utilize the battery 14 which furnishes current to the starting motor and to control the circuit 30, 31 by the same switch 33 that is utilized to start the motor 11.

The operation of my invention will be obvious from the above description. In starting an engine the push button 20 is pressed to operate the Bowden wire 25 for shifting the core or shell or both into a more effective position and the engine shaft is revolved by any means available for the purpose. In the constructions illustrated in Figures I and II the pressing of the push-button 20 not only shifts the magnetic conductor of the coil, but sets in operation the engine starter as well, and when the starter is permitted to cease operating, the spring 21 acting through the Bowden wire retracts the magnetic conductor. A similar result is brought about by the means illustrated in Figure IV, but instead of the Bowden wire connection I use an electrical connection by means of which an auxiliary coil 28 may be energized to shift the core and shell.

In addition to its use in the starting of an engine my invention may be employed if desired, for improving the spark at any time during the operation of the engine at low speeds. For this purpose I have shown in Figure III a control button 20 which has no connection with the starting mechanism.

While I have described my invention in more or less detail and as being embodied in certain forms, I do not desire or intend to be limited thereto, as quite to the contrary, my invention contemplates any proper changes in the form, construction and arrangement of the parts as well as the omission of immaterial elements and certain co-operating parts and the substitution of equivalents therefor, as circumstances may suggest or necessity render expedient.

I claim as my invention:

1. In an internal combustion engine, a starter, means for setting said starter in motion, an ignition system for the engine including an induction coil and means actuated by said first named means for increasing the magnetic permeability of the field of said coil.

2. In an internal combustion engine, a starter, means for setting said starter in motion, an ignition system including an induction coil, a metallic, magnetic conductor for said coil and means actuated by said first named means for increasing the extent of said magnetic conductor within the magnetic path of the coil.

3. In an internal combustion engine, a starter, means for setting said starter in motion, an ignition system including an induction coil, a metallic, magnetic conductor

- normally extending only partially into the magnetic path of said coil and means actuated by said first named means for moving said conductor further into said path.
4. In an internal combustion engine, an electric starting motor, an ignition system including an induction coil, a common source of current for said electric motor and induction coil, a switch controlling the connection between said current source and motor and means operated simultaneously with the closing of said switch for increasing the magnetic permeability of the field of said coil.
5. In an internal combustion engine, an electric motor, an ignition system including an induction coil, a metallic, magnetic conductor for said coil, a common source of current for said electric motor and induction coil, a switch controlling the connection between said current source and motor and means operated simultaneously with the closing of said switch for increasing the extent of said magnetic conductor within the magnetic path of the coil.
6. In an internal combustion engine, an electric starting motor, an ignition system including an induction coil, a metallic, magnetic conductor normally extending only partially through the magnetic path of said coil, a common source of current for said electric motor and induction coil, a switch controlling the connection between said current source and motor and means operated simultaneously with the closing of said switch for moving said magnetic conductor further into said path.
7. In an ignition system, an induction coil and electro-magnetic means for increasing the magnetic permeability of the field of said coil.
8. In an engine ignition system, an induction coil, a metallic magnetic conductor for said coil, an electro-magnetically operated means to increase the extent of said magnetic conductor within the magnetic path of the coil.
9. In an engine ignition system, an induction coil, a metallic magnetic conductor normally extending only partially into the magnetic path of said coil, an electro-magnetically operated means for moving said magnetic conductor further into said path, whereby the inductance of the coil at low engine speeds may be increased.
10. In an internal combustion engine, a starter, means for setting said starter in motion, an ignition system for the engine, including an induction coil, an electro-magnetically operated means actuated by said first named means for increasing the magnetic permeability of the field of said coil.
11. In an internal combustion engine, a starter, means for setting said starter in motion, an ignition system including an induction coil, a metallic magnetic conductor for said coil, and electro-magnetically operated means actuated by said first named means for increasing the extent of said magnetic conductor within the magnetic path of the coil.
12. In an internal combustion engine, a starter, means for setting said starter in motion, an ignition system including an induction coil, a metallic magnetic conductor extending only partially into the magnetic path of said coil, and electro-magnetically operated means actuated by said first named means for moving said magnetic conductor further into said path.
13. In an internal combustion engine, an electric starting motor, an ignition system including an induction coil, a common source of current for said electric motor and induction coil, a switch controlling connection between said current source and motor and electro-magnetic means operated simultaneously with the closing of said switch for increasing the magnetic permeability of the field of said coil.
14. In an internal combustion engine, an electric starting motor, an ignition system including an induction coil, a metallic magnetic conductor for said coil, a common source of current for said electric motor and induction coil, a switch controlling connection between said current source and motor and electro-magnetic means operated simultaneously with the closing of said switch for increasing the extent of said magnetic conductor within the magnetic path of the coil.
15. In an internal combustion engine, an electric starting motor, an ignition system including an induction coil, a metallic magnetic conductor normally extending only partially through the magnetic path of said coil, a common source of current for said electric motor and induction coil, a switch controlling the connection between said current source and motor, and electro-magnetic means operated simultaneously with the closing of said switch for moving said magnetic conductor further into said path.
16. In an ignition system, an induction coil, electro-magnetic means for increasing the magnetic permeability of said coil, a motor and single switching means for energizing both said motor and said electro-magnetic means.

In testimony whereof, I affix my signature. 120

OTTO E. HUEBNER.
